UNITED STATES PATENT OFFICE.

WILLIAM J. GIBBONS, OF PHILADELPHIA, PENNSYLVANIA.

SWITCH AND FUSE SUPPORTING BASE.

965,514.

Specification of Letters Patent. Patented July 26, 1910.

Application filed December 30, 1909. Serial No. 535,694.

To all whom it may concern:

Be it known that I, WILLIAM J. GIBBONS, a citizen of the United States, residing in the city and county of Philadelphia, State 5 of Pennsylvania, have invented certain new and useful Improvements in Switch and Fuse Supporting Bases, of which the following is a specification.

My invention relates to improvements in 10 switch and fuse supporting bases, and other similar devices, and it has for its object to provide a composite insulating support which is adapted to protect the fuses, switch connections and other circuit devices supported on the base from moisture.

Other objects and advantages of my invention will appear from the detailed description thereof which follows herein.

For the purpose of enabling a clear and 20 ready understanding of my invention, I have illustrated a convenient embodiment of the same in the accompanying drawings, but it will be understood that changes in the details of construction may be made 25 within the scope of the specification and claims without departing from my invention.

In the drawings:—Figure 1 is a top plan view of a base or support embodying my 30 invention and showing certain parts for completing a circuit supported thereon; and Fig. 2 is a section on the line 2—2 of Fig. 1.

Referring to the drawings:—1 designates the main base preferably of insulating material 35 such as porcelain or similar material, and 2 designates bars of insulating material supported in grooves or channels 3 formed in the upper side of the base or support 1. The bars 2 are secured to the porcelain base 40 1 by means of screws 4. The said bars 2 may consist of the same material as the base 1 or different material, such as slate.

5 designates a switch which is pivoted at 6 to posts or terminals 7. The said switch is 45 adapted to engage contact brushes at 8 which have connection in a known manner with fuses 9 supported in brackets 10.

The parts 7, 8 and 10 are mounted upon the insulating bars 2.

50 Heretofore, so far as I am aware, these

and similar parts have been mounted directly upon the insulating base 1 and the means for securing the said parts to the said base have extended entirely through the same. In such cases asbestos or similar material has been interposed between the base and the wall or other structure on which the said base is supported. The interposed material is pervious to moisture and in consequence the means employed for connecting 60 the parts similar to 7, 8 and 10 have been affected by moisture as have been other parts of the electric circuit, with the result that the successful operation of such devices has been impaired.

65 By mounting or supporting various parts such as the switches, fuses and other parts forming portions of the circuit upon the insulating bars 2, all such difficulty is avoided. When the said parts are connected or secured directly to the bars 2 they are protected against moisture from the wall or other structure on which the same is supported and in consequence no moisture is allowed to 70 pass from the wall or other supporting 75 structure to the operative parts.

In addition to the parts already described, I have shown a junction box 12 mounted upon the same base. The latter, however, constitutes no part of my present invention 80 which relates entirely to and consists entirely of the construction of an insulating supporting base consisting of two or more parts, one of which is a support or base for the other of said parts, and the latter constituting means to which the switch or 85 switches, fuses and other parts of an electric circuit are secured.

Having thus described my invention, I 90 claim:—

1. A support for the terminals, switches, fuses, and similar parts of an electric circuit consisting of a main base provided with a depression or seat formed therein and insulating material mounted in said depression 95 or seat to which said terminals, switches, fuses and similar parts are adapted to be secured.

2. A support for the terminals, switches, fuses and similar parts of an electric circuit 100

consisting of a main base provided with grooves or channels therein and bars of insulating material mounted in said grooves or channels to which said terminals, switches, fuses and similar parts are adapted to be secured.

In testimony that I claim the foregoing

as my invention, I have hereunto signed my name this 28th day of December, A. D. 1909.

WILLIAM J. GIBBONS.

In the presence of—
GEO. H. WEIDNER,
CYRUS N. ANDERSON.
